DRINKING CUP

Herbert Charles Behrens, Easton, Pa., assignor to American Can Company, New York, N.Y., a corporation of New Jersey

Filed Oct. 22, 1959, Ser. No. 58,033

Term of patent 14 years

(Cl. D44—9)

Fig. 1

FIGURE 2 is a fragmentary section taken on line 2—2 of FIGURE 1, on an enlarged scale to show the detail of the transparent thin innermost lamina.

The alternate rows of three and four apertures are repeated on the side opposite to that shown in FIGURE 1.

I claim:

The ornamental design for a drinking cup, substantially as shown and described.
